5 SHEETS—SHEET 1.

A technical diagram of a three-phase motor's stator winding. It features a central vertical line with two horizontal bars extending to the left and right. On the left, there are two vertical bars with horizontal bars above and below them, representing two slots per pole. On the right, there is a single vertical bar with horizontal bars above and below it, representing one slot per pole. The entire assembly is labeled with the number '6' at the bottom, indicating the槽数 (number of slots).

UNITED STATES PATENT OFFICE.

GEORGE H. BLANKMANN, OF ST. LOUIS, MISSOURI.

GRINDING-MILL.

1,231,478.

Specification of Letters Patent. Patented June 26, 1917.

Application filed August 30, 1916. Serial No. 117,670.

To all whom it may concern:

Be it known that I, GEORGE H. BLANKMANN, a citizen of the United States, residing at St. Louis, State of Missouri, have 5 invented certain new and useful Improvements in Grinding-Mills, of which the following is a full, clear, and exact description, reference being had to the accompanying drawings, forming a part hereof.

10 My invention has relation to improvements in grinding mills; and it consists in the novel features of construction more fully set forth in the specification and pointed out in the claims.

15 The present improvement is directed to that class of pulverizers which are particularly adapted for the grinding of grain, coffee, spices, and like substances where the grinding of the material is attended with 20 the production of more or less waste in the form of chaff or light particles readily separated from the finished product with the aid of air currents traversing the grinding chamber of the mill, and which, if desired 25 may be returned to the mill by these same air currents for purposes of regrinding or further treatment. The object of the invention is to construct a mill of the character referred to which will have a maximum capac-

30 ity for a given size mill; to reduce the power required per ton of output; to provide a structure according ready access to the several operating parts of the mill for purposes of adjustment; to provide facilities for 35 the renewal of worn out parts; to provide means for the pulverizing of materials of different degrees of hardness and friability; to provide means for regulating the intensity 40 of the air currents operating on the pulverized material; to provide means for regulating the size of the pulverized particles; to provide a structure whose moving parts shall operate with a minimum amount of 45 friction thereby reducing the power necessary for driving the same; to provide a structure whose principle of operation may be applied to the grinding of material and substances other than those above specifically enumerated; and further to provide 50 further and other features of construction the advantages of which will be fully apparent from a detailed description of the invention in connection with the accompanying drawings in which—

55 Figure 1 represents a side elevation of the mill, certain parts being in section; Fig. 2

is a front elevation thereof; Fig. 3 is a vertical longitudinal section on the line 3—3 of Fig. 2; Fig. 4 is a vertical cross-section on the line 4—4 of Fig. 3; Fig. 5 is a horizontal section on the line 5—5 of Fig. 3; Fig. 6 is a vertical sectional detail on the line 6—6 of Fig. 4; Fig. 7 is a horizontal sectional detail on the line 7—7 of Fig. 1; Fig. 8 is a vertical sectional detail on the line 8—8 of Fig. 7; Fig. 9 is an end view of one-half of the rotor member with parts removed or broken away to expose successive portions entering into its construction; Fig. 10 is a half side elevation 60 of the rotor and half longitudinal section on the line 10—10 of Fig. 9; Fig. 11 is a longitudinal sectional detail of the "fan" portion only, of the rotor on the line 11—11 of Fig. 9, the terminal rotatable ring being removed; Fig. 12 is a detached plan view of 70 one of the grinding bars; Fig. 13 is a cross-section on the line 13—13 of Fig. 12; Fig. 14 is a similar cross-section of the bar turned end for end; Fig. 15 is a detached plan of 75 one of the scroll rings between which the grinding bars are mounted; and Fig. 16 is an enlarged sectional detail on the line 16—16 of Fig. 3.

Referring to the drawings, 1 represents 80 a frame or mill housing provided with the side bearing-supports or brackets 2, 3, respectively, the free ends of said brackets respectively carrying the roller bearings 4, 4', which support the transversely disposed rotor shaft S, the ends of the shaft being reduced as at S', S'', said reduced ends carrying the crown driving pulley P and the flywheel W, respectively. Keyed, or otherwise secured to the shaft S is the hub 5 of the 85 "fan" member of the rotor, said fan being provided with a series of radial blades 6 diverging longitudinally in opposite directions from a central annular peripheral collar or rib 7 of the hub, and reinforced by a 90 central web 8 leading from said collar, the outer ends of the blades terminating in the annular heads or rings 9 which project radially beyond the free edges of the blades (Fig. 11) the inner edges of the rings being 95 provided with annular shoulders 8 around the openings O of the rings, said shoulders forming seats or bearings for the rotatably adjustable outer controlling rings 10 by means of which, as presently to be seen, the 100 beaters or cutters of the rotor are adjusted relatively to the grinding or breaker bars. 105

The rings 9 forming the rotor heads or ends are provided at points between the blades 6 with radial slots a the bottoms of which are removed a suitable distance radially 5 from the surfaces of the shoulders s , the rings 10 on the other hand being provided with curved or arcuate slots a' having outer reversely curved terminals a'' , the lengths of the respective slots a , a' , being such that 10 when the bottoms of any pair of slots are in alinement, the terminal a'' of the slot a' is radially in alinement with the outer end of the slot a of the next pair as fully shown in Fig. 9. Disposed between the blades 6 of the rotor 15 and traversing the slots a , a' , of the members 9, 10, thereof, are cylindrical rods 11 to which are loosely hinged the beaters or cutters 12 wedge shaped in cross section and flaring outwardly, the said members 12 being 20 preferably provided with lugs or ears e through which the rods 11 loosely pass. By loosening the terminal nuts n on the rods 11, the rings 10 are left free to be turned or rotated on their seats s . If for example we 25 rotate the rings 10 in the direction shown by the curved arrow in Fig. 9, that is, toward the left, the effect of the slots a' would be to constrain the series of rods 11 to move radially outward in the slots a of the rings 30 9, thereby moving outwardly the entire series of beaters or cutters 12 or to the dotted positions shown in said figure. The innermost or fully retracted position of the beaters or cutters is when the hinge-rods 11 35 thereof are at the bottoms of the coöperating slots a , a' , in which position they are shown in Fig. 9. Once the members 12 are adjusted radially to any predetermined position, the nuts n are driven home and the 40 parts tightened as well understood by the skilled mechanic.

The beaters 12 may be considered as the radially adjustable parts of the rotor member, the "fan" portion or the part comprising the blades 6 and heads 9 being the fixed or body member, and the rings 10, 10, being the rotatably adjustable members, but collectively all constituting the rotor, or rotary member of the grinding portion of the 45 mill. Coöperating with the beaters 12 are the grinding or breaking bars 13 substantially of the cross-section shown in Figs. 3, 13, 14, two opposite faces being provided with longitudinal grinding ribs h having 50 curved faces t intersected by the plane undercut faces t' , the intersections forming cutting edges as shown (Figs. 13, 14). The curved faces of the opposing ribs are disposed in reverse directions whereby by turning 55 the bar end for end either the curved surfaces or the sharp cutting edges of the ribs may be presented to the beaters 12 as clearly obvious from Figs. 13, 14. The bars 13 terminate in reduced ends or trunnions 60 14 which are received by the spiral grooves 14 which are received by the spiral grooves 65

or ways d of the scroll gear-rings 15 disposed on opposite sides on the inside of the housing 1. The scroll ring 15 on one side of the apparatus rests loosely on the cylindrical or web portion of the Z-ring 16 forming the air intake head of the casing or housing 1, the ring on the opposite side resting loosely on the corresponding cylindrical portion of the head 17 which last mentioned head has cast as an integral part thereof the 70 return chute 18 and hopper 19 as shown in Fig. 4. Each ring 15 is maintained against lateral displacement on its cylindrical or annular bearing by a segmental angle ring 20 secured to the inner side walls of the casing 1, and by corresponding diametrically disposed segmental angle rings 21 secured to the side arcuate hinge members 22 of a swinging lid 23 hinged to a rod 24 between the lugs 25 formed on the front wall of the 75 casing or housing 1. The purpose of the lid 23 is to afford access to the interior of the casing when necessary.

Simultaneous rotation may be imparted to the scroll rings 15 by means of a shaft 26 90 provided with pinions 27 meshing with the teeth of the respective scroll rings. To the shaft 26 rotation may be imparted in one of two ways, to wit: (1) Mounted loosely in a bearing 28 cast with the casing wall is an 95 eccentric 29 terminating in an enlarged head 30 resting on the bearing, said head being provided with an operating handle 31. The eccentric is traversed loosely by a spindle 32 terminating at the bottom in a worm 33 which meshes with a worm wheel or pinion 34 at the adjacent end of the shaft 26, the upper end of the spindle terminating in a hand-wheel 35. It will be seen from the foregoing that by turning the hand-wheel, 100 rotation will be imparted to the shaft or spindle 32 and through the gears 33, 34, to the shaft 26, the latter in turn imparting rotation to the scroll gear rings 15. The method described may be considered as the 105 slow method, but to rotate the scroll rings rapidly I make the following provision, to wit: (2) By giving the handle 31 a sufficient turn in proper direction, the eccentric 29 will be turned in its bearing or "strap" 28 110 so as to draw away the spindle 32 from the worm gear 34 and hence disengage the worm 33 from said worm gear. This leaves the shaft 26 free to be operated quickly by hand for which purpose said shaft is provided 115 with a terminal crank handle 36 by which it may be given a quick turn independent of the hand wheel 35. With the rotation of the scroll rings 15, the grinding bars 13 mounted loosely as they are in the grooves d thereof 120 will be caused to approach or recede from the common axis of rotation of the rings according to the direction of rotation imparted to the rings. In other words the spiral grooves d will "screw" or drive the bars to 125 130

ward the axis with a rotation of the rings in one direction, and "unscrew" or drive the bars away from the axis with a rotation in the opposite direction. In their movement 5 toward the axis, the bars will approach the outer terminals of the beaters 12; and in their movement from the axis, they will move away from the beaters. Since the beaters are themselves radially adjustable, 10 it follows that the distance between the members 12 and 13 may be carefully regulated according to the character of finished product desired, or the fineness to which the material shall be ground. In 15 Fig. 15 if we assume the ring 15 to be sufficiently rotated in the direction indicated by the curved arrow, the center line x of the bars 13 will assume the position x' the bars having traveled toward the axis of the ring. 20 Of course, during the rotation of the scroll rings, provision must be made to prevent the grinding bars from being carried around with the rings, that is to say, the bars must be held against circular or rotary displacement, 25 their travel being confined to radial paths to and from the common axis of the rings or axis of the rotor. This rotary displacement is prevented in one direction by the front wall of the feed chute 37 against 30 which the lid 23 closes, and against the bottom of which (serving as an abutment) the upper terminal grinding bar bears, and in the opposite direction rotary displacement is prevented by the lower terminal grinding 35 bar bearing against the adjacent strip 38 forming the lower transverse member of the frame carrying the curved or concaved apron or deflector 39, the sides of the frame being in the form of arcuate or bowed angle 40 members 40 as shown (Figs. 3, 5). The terminals of the strip 38 are provided with studs 41 which operate in the grooves d of the scroll rings, the same as do the trunnions 14 of the grinding bars 13. The vertical 45 legs of the angle members 40 are provided with elongated slots u traversed by screw studs 42 carrying nuts n' by which the apron can be adjusted relatively to the grinding bars confined between the scroll 50 rings, the slots u , and the studs 41 which traverse the grooves d permitting the apron to accommodate itself to any rotations imparted to the scroll rings for purposes of adjusting the grinding bars as presently to be 55 more clearly apparent. Should it be desired to remove the grinding bars from the scroll rings for purposes of turning them end for end, or to rotate them about their axes to present the unused grinding faces thereof to 60 the beaters, the apron 39 is lifted far enough out of the way to permit access to and manipulation of the bars by sliding the slotted members 40, say to the dotted-position indicated in Fig. 3, the slots u being of sufficient 65 length to allow for the necessary movement

of the apron; and when the apron has been shifted to the proper position it may be held there for the time being by tightening the nuts n' .

The disposition of the outer ends of the 70 beaters 12 being along the surface of a cylinder, and that of the inner faces of the grinding bars 13 along a spiral surface, it follows that the space between the beaters and grinding bars through which the material must pass while being ground will be widest at the discharge end of the chute 37 and gradually taper to an edge at a point near the last of the series of grinding bars, 75 the progressively diminishing space causing the material to be progressively ground or reduced as clearly obvious from the drawings (Fig. 3).

The material is charged into the hopper 43, the latter being provided with an inclined platform 44 to which is hinged a gravity valve or gate 45 which allows the material to gravitate into the chute 37, the quantity being regulated by a slide or gate valve 46 operating through a slot in the 90 front wall of the chute, said valve being connected to a U-shaped frame 47 whose terminal arms operate in bearings 48. The valve 45 as arranged prevents the escape of dust from the machine. The pulverized material 95 is discharged from the rotor-casing through an uptake 49 whence it passes into the conical bottom of the separating or expansion chamber 50, whence the very fine product or chaff passes through the conical top of said 100 chamber into an elbow 51 from which it is discharged through the square terminal 51' thereof, tangentially along the wall of the "cyclone" collector 52, the latter being provided with a discharge spout 53 controlled 105 by a weighted gravity valve 54 as shown, the valve being balanced by a weight 55 on the arm 56 leading from the hinge axis of the valve.

Leading from the bottom of the separating chamber 50 is the inclined tailings spout 57 the heavier material being discharged therefrom to any point of further treatment by the slide or gate valve 58 at the lower end of the spout, or, if desired, such material 110 may be returned to the mill for further grinding through the branch conduit or spout 59 the intake end of which is controlled by the hinged damper or valve 60 which when closing the spout 57 rests 115 against a ledge or strip 61 in which position of the valve, the material is returned to the mill through the return spout 59, the material being discharged into the chute 37 beneath the platform 44. The pulverized material in traversing the uptake 49 and chamber 50 flows through the funnel 62, between a deflecting cone 63 and a double truncated cone deflecting hood 64, around an auxiliary deflecting cone 65, the lighter 120 125 130

particles (always accompanied by air) flowing through the elbow 51 from the square outlet 51' of which the current is discharged tangentially into the collector 52 as previously described, the heavy particles dropping behind, to the bottom of conical bottom of the chamber 50, whence they flow into the spout 57 previously referred to.

10 Leading from the top of the collector 52 is a surplus air-return pipe 66 the base of which discharges into the hopper 19 previously referred to. The intake end of the pipe 66 leads from the reduced terminal 67 of the bell-shaped hood or air regulator or valve 68 operating in conjunction with the deflecting cone 69 secured by straps 70 to the collector walls. The depending cylindrical portion of the member 68 is provided 20 with slots *w* which the straps may enter with any material lowering of the said regulator member. This member is raised or lowered according to circumstances presently to be explained by means of the three 25 (or more) screw-threaded hanger rods 71 leading from the regulator through the roof of the collector 52, the upper screw-threaded portions of the rods above said roof being provided with sprocket nuts or wheels 72, 30 one of which has formed therewith a hand wheel 73, the series of sprocket nuts or wheels being connected by a sprocket chain 74. It follows therefore that when rotation is imparted to the hand wheel 73 in proper 35 direction, the rods and hence the regulator member will be raised or lowered as the case may be, thereby either enlarging or constricting the annular air passage *p* between the members 68 and 69. The discharge end 40 of the pipe 66 above the hopper 19 is provided with a vent 75 controlled at the intake end by a slide or gate valve 76 for regulating the return draft and the influx of atmospheric accessions to said draft. A second 45 regulating valve or damper 77 may be positioned in the pipe 66 above the vent 75.

Regulating the initial air influx into the rotor casing is a bell or cone valve 78 terminating in a grooved hub or neck feathered 50 to the shaft S, the groove being loosely embraced by a yoke or ring 79 to which are pivotally secured the inner ends of the diametrically disposed links 80, the outer ends of the links being pivotally secured to the 55 sides of the medial loop 81 of an operating lever 82 whose lower forked end is pivoted about a fulcrum rod 83 mounted rigidly between the brackets 3, 3, (Fig. 6) said lever having pivoted thereto above the shaft S, a 60 locking pawl or lever 84 whose short arm is controlled by a flexed spring 85, the long arm terminating in two or more teeth meshing with the teeth of a locking disk 86 secured to the rod 83 between the fork members 65 of the operating lever 82. The locking

pawl 84 is formed with a medial loop 84' through which, and through the loop 81 of the operating lever 82, the shaft S freely passes and from which loops it is sufficiently spaced to allow for the necessary oscillations 70 of the operating lever for purposes of shifting the position of the valve 78 relatively to the intake opening O of the terminal rotor ring 9. By tripping the pawl 84 to the position indicated by the outer dotted line in 75 Fig. 4, that is to say to a position to disengage the toothed end from the disk 86, the lever 82 will be left free to swing about the axis of the rod 83, and hence move the valve 78 in or out according to the size of opening 80 desired through the rotor head or ring 9, the opening O' in the casing head 16 not being affected. The controlling means for the valve 78 is well understood in the art and is shown here more or less conventionally, the 85 shifting of the valve along the shaft S while the latter is rotating being akin to the action of well known clutch mechanisms with which the skilled mechanic is familiar. The casing 1 is provided where convenient with 90 hand-hole covers 87, 88, 89, as shown. Obviously, I may depart from the details shown without affecting the nature or spirit of my invention.

The operation may briefly be described as 95 follows: Rotation being imparted to the rotor shaft S in the direction indicated by the curved arrow in Fig. 3, the grain or other material is introduced into the hopper 43 whence it gravitates past the valve 45 into 100 the chute 37, the quantity of flow being controlled by the slide valve 46 operating across the chute. The material thus reaches the outer ends of the beaters 12 carried around by the rotor and is caused to pass between 105 the beaters and the ribbed faces of the grinding bars 13, the bars being mounted to present either the sharp edges to the rotating beaters (see Fig. 3) or, where the material to be crushed is friable the rounded faces of 110 the ribs may be thus presented to the beaters (Fig. 13). The distance between the outer ends of the beaters 12 and the grinding faces of the bars 13 is determined by, and the parts respectively adjusted through, the instrumentality of the rotatable rings 10 by which the position of the beaters is radially adjusted as already described, and by the scroll rings 15 by which the positions of the grinding bars is adjusted along the spiral groove 115 *d*. If for example we wish to "contract" the curve of grinding bars as shown in Fig. 3, we turn the scroll-rings contrary to the direction of the hands of the clock (Fig. 15) which would have the effect of driving the 120 bars into the inner or narrower portions of the spiral groove *d*. In thus turning the scroll rings, the upper terminal member of the series of grinding bars bearing as it does 125 against the fixed wall of the chute 37 (Fig. 130

3) can not move with the scroll rings (being held against rotary movement by said wall) so that rotary movement of the bars is impossible. The bars are thus constrained to 5 move radially inward by their traverse of the gradually diminishing curves of the grooves *d*. Thus the entire series of grinding bars move toward the axis of the scroll rings with a rotation of the rings in the direction indicated, the studs 41 of the bar 38 of the deflecting apron 39 being likewise caused to follow in grooves *d* toward the axis of the scroll rings, this action having the effect of lifting the free end of the apron 10 and causing an upward oscillation thereof about the common axis of the screw studs 42. The grinding bars 13 however which have now been contracted into a smaller compass (that is to say smaller in the sense 15 that the radii of the spiral curve diminish as the curve approaches the center of the scroll ring) will necessarily crowd the apron 39 and cause the same to be pushed upward, it being understood that the nuts *n'* are 20 loosened sufficiently to allow for this movement of the apron, said movement being permitted by the slots *u* previously described. The material ground between the rotor beaters 12 and the grinding bars 13 is discharged 25 across the deflecting apron 39 into the uptake 49, the centrifugal action of the "fan" of the rotor drawing in atmospheric air through the opening *O* of the ring 9 thereof, and through the opening *O'* of the head 16 30 of the casing, and discharging the dust laden currents into the uptake 49 as above specified. It is of course to be understood that the air valve 78 is set to proper position to allow for the passage through the opening 35 *O* of the proper amount of air to produce the desired circulation through the rotor and the casing thereof. From the uptake 49 the currents pass into the expansion or separating chamber 50 where the heavier particles 40 or tailings are dropped, the same gravitating into the spout 57 whence they are either discharged past the valve 58, or are diverted by the valve 60 into the return chute 59 which delivers the material back to the chute 45 50 57 leading from the hopper 43. The lighter particles from the separating chamber 50 are carried onward through the pipe 51 and are discharged from the mouth 51' thereof tangentially along the walls of the collector 52, 55 said tangential projection of the currents producing a vortex or "cyclone" within the said collector 52, said vortex resulting in an axial zone of comparative quiet through which the heavier particles drop into the 60 spout 53 whence they may be discharged past the gravity valve 54. The lightest particles and surplus air are returned from the collector 52 back to the rotor casing through the conduit 66, which may if desired receive 65 accessions of fresh atmospheric air through

the vent pipe 75 as already described. Should it be desired for any reason to return a portion of the heavier particles from the collector 52 back to the rotor casing with the returned air, the valve 68 may be lowered 70 sufficiently to materially constrict the passageway *p* (Fig. 1) which will have the effect of accelerating the velocity of the currents traversing the same, such accelerated currents picking up the desired heavier particles and returning them to the mill for 75 regrinding. It will thus be seen that the character of the final product of the mill may be regulated according to circumstances, it being possible at all times to return any portion or all of the initially ground product 80 back to the mill for regrinding. The apparatus moreover is self-contained, the air entering the rotor through the opening *O* being in a large measure returned to the rotor 85 by the conduit 66.

Having described by invention what I claim is:

1. In a mill of the character described, a rotor, radial beaters mounted thereon, 90 grinding bars disposed helically about the cylindrical path of the outer ends of the beaters, and rotatable members provided with spiral grooves or ways traversed by the terminals of the bars for radially adjusting the bars as a unit, toward and from 95 said beaters.
2. In a mill of the character described, a rotatable scroll-ring provided with a spiral groove on one face thereof, grinding bars 100 operating to traverse said groove with a rotation of the ring, and means for preventing rotary displacement of the bars during the rotation of the ring.
3. In a mill of the character described, a 105 pair of scroll-rings spaced apart and rotatable in unison about a common axis, spiral grooves formed on the inner opposed faces of the rings, grinding bars disposed between the rings and terminating in trunnions 110 traversing the grooves upon rotation of the rings, whereby the bars may approach or recede from the axis aforesaid, depending on the direction of rotation of the rings.
4. In a mill of the character described, a 115 pair of scroll gear-rings spaced apart and rotatable in unison about their common axis, spiral grooves formed on the inner opposed faces of the rings, grinding bars disposed between the rings and traversing the grooves 120 thereof, a shaft provided with pinions engaging the teeth of the scroll rings, and means for imparting rotation to said shaft.
5. In a mill of the character described, 125 grinding bars having each a plurality of adjacently disposed ribbed formations provided with curved faces intersected by undercut faces on opposite sides of the bar, the formations being parallel to the longitudinal axis of the bar and those on one 130

side being reverse from those on the opposite side whereby when the bar is turned end for end either the curved face or the cutting edge of the undercut face is available for grinding.

6. In a mill of the character described, a suitable casing, a rotor mounted therein comprising a shaft, a series of radial blades disposed about the shaft, rings terminating 10 the blades, the opening of one of the rings serving as an air intake, a bell valve slid- 50 ingly feathered to the shaft for controlling the intake opening aforesaid and means for actuating said valve.
- 15 7. In a mill of the character described, a rotor comprising a member provided with a series of radial blades terminating in annular heads, annular shoulders formed on the outer faces of the heads, controlling 20 rings rotatable about the shoulders and pro- 55 vided with arcuate or curved slots beyond the shoulders opening through the periph- 60 eries of the rings, radial slots formed on the rotor heads, hinge rods jointly traversing 25 the slots of the heads and rings, beaters 65 pivotally secured to the rods between the heads of the rotor, a rotation of the rings constraining the rods to traverse the radial 70 slots of the heads whereby radial adjust- 75 ment of the beaters may be effected, and means on the rods for clamping the parts against displacement when once adjusted.
8. In a mill of the character described, a 30 pair of rotatable scroll-rings spaced apart 35 and provided with spiral grooves on their opposing or adjacent faces, a rotor casing 40 for housing the rings, a series of grinding bars mounted between the rings and traversing the spiral grooves thereof with a rotation of the rings, a deflector apron free to

yield about a fixed axis of support, mounted within the rotor casing, the free ends of the sides of the apron being provided with studs operating in the grooves of the scroll-rings, the free end of the apron serving as a yield- 45 ing bearing for the adjacent terminal member of the series of grinding bars mounted between the rings, and a fixed abutment for engaging the terminal member at the opposite end of the series of grinding bars, 50 whereby upon rotation of the scroll-rings the grinding bars may be made to approach or recede from the common rotation axis of the rings, according to the direction in which the rings are turned.

9. In a mill of the character described a longitudinally serrated reversible grinding bar having teeth on opposite sides thereof with gradually curved surfaces meeting the cutting edges of the teeth, said teeth 60 being inclined in reversed order on opposite sides of the bar.

10. In a mill of the character described, a rotor casing, terminal annular heads for the same each provided with a cylindrical 65 portion forming a seat or bearing, a scroll ring seated loosely on said cylindrical portion, arcuate angle-bar segments secured to the casing walls for maintaining the scrolls against lateral displacement on their cylindrical seats, a hinged lid or cover, and similar angle-bar segments on the sides of the lid for protecting the scroll at points removed from the first mentioned segments.

In testimony whereof I affix my signature, in presence of two witnesses.

GEORGE H. BLANKMANN.
